UNITED STATES PATENT OFFICE.

ROGER L. KNUTSSON, OF ROCKFORD, ILLINOIS, ASSIGNOR OF ONE-HALF TO EDGAR C. ALLEN, OF ROCKFORD, ILLINOIS.

MERCURY SWITCH.

Application filed October 16, 1924. Serial No. 743,951.

This invention relates to mercury switches and particularly to a mercury switch having a construction permitting it to be readily connected to a suitable socket in order to obtain quick and easy electrical connection thereto. The growing demand for mercury switches in various arts has resulted in uses therefor which call for mounting a switch in a movable part, the motion of which 10 serves to actuate the switch. In such uses it is, of course, necessary to have electrical connection thereto and frequently the character of the switch mounting makes it difficult to secure a simple arrangement for a 15 proper and efficient electrical connection to a switch.

It is the object of the present invention to provide a mercury switch construction adapted to permit electrical connection there- 20 to by a plug and a socket relation.

A particular object of the invention is to provide a mercury switch capable of using a standard bayonet socket of the type employing a single central contact.

25 A further object of the invention is to provide a switch presenting generally at its external surface an insulating medium.

In the drawings, Figure 1 illustrates a switch and a socket in separated relation.

30 Fig. 2 shows a longitudinal section of a switch having a metal thimble within an insulating tube.

Fig. 3 shows a modified form of the switch in Fig. 2 in which a metallic band replaces the metallic thimble.

Fig. 4 is a fragmentary view like Fig. 3 showing a modified construction of the metallic band.

Fig. 5 is a cross section of the switch of Fig. 2 on the line 5—5 thereof.

The body of the switch consists of a tubular open-ended cylindrical casing 6 of a suitable insulating material, such as fiber or bakelite, which may be molded to the required form as shown in Fig. 2. The casing 6 has a metallic thimble or lining 7 on its interior which serves as one contact to the mercury. The thimble may be flared or expanded at its open end 8 and thus molded 45 into the wall of the casing 6 to form a unitary switch body with a metallic lining. At one end of the casing there is a plug 9 of insulating material such as fiber or bakelite. The plug fits tightly within the opening of 55 the tubular member 6 and is provided with

an overlapping flange 10, the edge of which lies flush with the outside of the casing 6, thus forming a continuously cylindrical switch body. On the interior of the casing, the plug has a centrally located rounding 60 projection 11 through the center of which a single contact 12 extends. The contact projects from the plug to a slight extent into the interior of the casing in order to afford sufficient surface to make contact with a 65 globule of mercury 13. At the outside of the cap or plug 9 a depression 14 is formed centrally in the material thereof into which the other end of the contact 12 extends. A thin metallic washer 15 is placed in the bottom 70 of the depression 14, over which solder 16 is placed to fill the depression, the solder preferably protruding to a slight extent above the flat surface of the plug end. Pins 17 and 18 pass through the casing 6 into the 75 plug 9 to secure the parts together and also to provide attaching means for use in the socket illustrated. In the present instance the pins pass through the metallic thimble and thus form an electrical connection to the 80 ground.

Fig. 1 illustrates a standard single-contact bayonet socket comprising a tubular member 19 to receive the switch herein disclosed. A single spring-pressed contact 20 located 85 centrally of the socket makes contact with the solder 16. Bayonet slots 21 and 22 of usual construction receive the pins 17 and 18 in a well known manner, thereby completing electrical connection to the switch through 90 the solder 16 and the pins 17 and 18.

In Fig. 3 there is shown a modification of the switch above described in which a portion of the metallic lining is eliminated. A lining ring 23 of conducting material, preferably metal, is located in the vicinity of the contact 12 so that the mercury 13 will have electrical connection therewith when the switch is tilted to place the contact end thereof lowermost. As in the first instance electrical connection is made through pins 17 and 18. It will be observed that the ring 23 has an enlarged portion 24 thereon by which it is rigidly held in the casing 6, the same being preferably moulded in a bakelite casing. In this instance, the ring 23 is set into the body of the casing 6 with its opening flush with the interior thereof, thereby providing the receiving opening for the plug 9. In Fig. 4, a slightly modified ring 110

construction is shown, the ring having a portion 25 projecting into the interior of the casing forming an annular ledge or ridge 25 therein.

6 In operation the mercury flows from end to end as the switch is tilted. Upon reaching the contact end of the switch the mercury has little tendency to bounce away therefrom because of the rounded or inclined 10 form of the projection 8. This assures a ready functioning of the switch without a preliminary cutting off of current which might result if the mercury should jump away from the end because of impact 15 therewith. In the form shown in Fig. 2 the use of a metallic thimble or lining within the insulating casing 6 materially strengthens the structure of the switch and thus adapts the same to a variety of uses. In 20 the form shown in Fig. 3 the ring 23 performs the electrical functions of the metallic thimble 7, the elimination of which lowers the cost of manufacture of the switch. In both instances it will be observed that the 25 switch receives its two electrical connections through the socket shown in Fig. 1, yet the switch body itself is comprised entirely of insulating material except at the contacts 16, 17 and 18. Thus, the switch may be 30 mounted in a movable body without danger of grounding through the switch casing. The annular form of one contact encircling the other permits the switch to be mounted without the necessity of having a particular 35 side thereof uppermost. Thus the necessity of marking that side with the designation "Up" is obviated.

I claim as my invention:

1. A quick-detachable mercury switch 40 adapted for insertion into a bayonet-slotted socket having a single central contact, said switch comprising, in combination, a casing of insulating material, a metallic lining in said casing near one end thereof, a single 45 contact in the casing at said end passing therethrough to the interior of the casing in the vicinity of said metallic lining, the outer

end of said contact being centrally located on said end of the casing and adapted for electrical connection with the central contact of the socket, mercury in said casing, and a pin projecting outwardly from said casing for engagement with the bayonet slot of the socket, said pin passing through said casing to touch said lining whereby to effect 55 electrical connection thereto.

2. A quick-detachable mercury switch adapted for insertion into a bayonet-slotted socket having a single central contact, said switch comprising, in combination, a metallic thimble, insulating material covering and enclosing said thimble, a single contact extending through said material into the interior of the casing adjacent to one end of the thimble, the outer end of said contact being centrally located on the end of the casing and adapted for electrical connection with the central contact of the socket, mercury in said thimble, and a pin projecting outwardly from the casing adapted to enter the bayonet slot of the socket, said pin passing through said material and touching said thimble whereby to effect electrical connection thereto.

3. A quick-detachable mercury switch 75 adapted for insertion into a bayonet-slotted socket having a single central contact, said switch comprising, in combination, a casing of insulating material composed of two sections forming an elongated chamber within 80 the casing, mercury in said chamber, a single contact at one end of the casing adapted to engage electrically the central contact of the socket, an annular contact in the casing near the first contact, and a metallic pin 85 projecting outwardly from the casing adapted to enter the bayonet slot of the socket, said pin passing through said casing to said annular contact to serve as one connection to said switch.

In testimony whereof, I have hereunto affixed my signature.

ROGER L. KNUTSSON.
